UNITED STATES PATENT OFFICE.

JOHN M. SAILER, OF JANEVILLE, WISCONSIN, ASSIGNOR OF ONE-HALF TO WILLIAM MUSSER, OF IOWA CITY, IOWA.

INTERNAL-COMBUSTION ENGINE.

1,042,975.

Specification of Letters Patent.

Patented Oct. 29, 1912.

Application filed May 10, 1910. Serial No. 560,403.

To all whom it may concern.

Be it known that I, JOHN M. SAILER, a citizen of the United States, residing at Janesville, county of Rock, State of Wisconsin, have invented certain new and useful Improvements in Internal-Combustion Engines, of which the following is a specification.

This invention relates to improvements in internal combustion engines.

The main objects of this invention are, first, to provide an improved explosion engine which is powerful and at the same time compact; second, to provide in an improved explosion engine an improved arrangement of cylinders whereby the power is most effectively delivered to the crank shaft; third, to provide in an explosion engine an improved means for supplying or delivering the explosive mixture to the engine cylinders.

Further objects and objects relating to structural detail will definitely appear from the detailed description to follow.

I accomplish the objects of my invention by the devices and means described in the following specification.

The structure described constitutes one effective embodiment of my invention.

Other embodiments would be readily devised by those skilled in the art.

The invention is clearly defined and pointed out in the claims.

A structure constituting an effective and preferred embodiment of the features of my invention is clearly illustrated in the accompanying drawing, forming a part of this specification, in which:

Figure 1 is a plan view of a structure embodying the features of my invention, portions being broken away to show structural details. Fig. 2 is a detail vertical section taken on a line corresponding to line 2-2 of Fig. 1. Fig. 3 is a vertical section through the charging cylinders, taken on a line corresponding to line 3-3 of Fig. 1. Fig. 4 is a corresponding vertical section through the lower portion of the charging cylinders and the crank casing, taken on a line corresponding to line 4-4 of Fig. 2. Fig. 5 is a detail vertical section taken on a line corresponding to line 5-5 of Fig. 1, showing details of the charge delivery connections to the engine cylinder.

In the drawings, similar reference numerals refer to similar parts throughout the several views and the sectional views are taken looking in the direction of the little arrows at the ends of the section lines. 55

Referring to the drawing, I provide a plurality of engine cylinders, the structure illustrated having four, which are designated generally by the numerals 1, 2, 3, and 4. These cylinders are provided with suitable water jackets, which, however, form no part of my present invention and are therefore not described in detail herein. 60 65

The cylinders are arranged in sets; that is, the cylinders 1 and 3 form one set and the cylinders 2 and 4 the other. The engine pistons 5 are shown in the drawing in their central position, one pair of pistons being on their out stroke and the other on their in stroke. These pistons are connected to the common crank shaft 6 by means of the piston rods 7. 70 75

The engine cylinders, in the structure shown in the drawing, are horizontally disposed and cast integrally with a central casing-like body 8, into which they open at their inner ends. A charging cylinder 9 is provided for each set of engine cylinders. These charging cylinders are mounted on the casing 8 (see Fig. 2). These charging cylinders are connected to a carburetor, as 85 10, where a carburetor is used, through the pipe 11 and the chambers 12, the chambers 12 being connected to the charging cylinders through ports controlled by the check valves 13. The pipe 11 has branches 14 connecting it with these chambers 12. Both the charging cylinders are connected through ports controlled by the check valves 15 to the charging chamber 16. This charging chamber is connected through the delivery 90 95 pipes 17 and the headers 18 to the cylinders, the connection for the headers to the outer ends of the cylinders being controlled by the cylinder inlet valves 19. The charging cylinders are preferably connected by the pipe, as 20, having a valve 21 therein. By the manipulation of this by-pass connection for the charging cylinders, the quantity of charge delivered to the cylinders may be regulated, as is obvious, as, if the valve is 100 open or partially open, more or less of the charge will pass from one charging cylinder to the other instead of to the charging

105

chamber 16. The valve illustrated is a hand controlled globe valve. A valve controlled by a governor may be substituted therefor if desired. By thus arranging and connecting the cylinders, all the cylinders of a set are charged with the same pressure and quality of explosive mixture, thus maintaining an even stroke for the engine and securing a balanced working thereof.

10 The plungers or pistons 22 for the charging cylinders are connected by their piston rods 23 to the crank shaft 6, the piston rods of oppositely arranged engines and one of the charging cylinders being in the same vertical plane, so that the strain on the crank shaft is minimized. The connections for the piston rods to the engine and charging pistons preferably consist of segment bearing members 24 on the piston rods 7, arranged to engage the crank shaft. The piston rods 23 are provided with cross pieces 25 at their inner ends, to which the segment-like bearing members 26 are connected, the bearing members 26 being adapted to embrace the bearing members 24 of the piston rods 7. This provides a very simple connection for the piston rods to the crank shaft and at the same time one which is very strong and durable, and enables the placing 25 of the cylinders in alignment so that two of the engines and one of the charging cylinders are connected to the same crank offset of the crank shaft. The bottom of the casting 8 is adapted to serve as a lubricant receptacle, so that the crank shaft, striking into the lubricant as the crank shaft revolves, splashes the same onto the bearings.

30 My improved engine is very powerful in proportion to the fuel consumed and runs 35 at a comparatively even speed.

40 I have illustrated my invention in a simple embodiment thereof, which I found practical. I am aware, however, that structural details can be greatly varied and I desire to 45 be understood as claiming the same, but as these details will be very readily understood by those skilled in this art, I have not attempted to illustrate or describe the same herein.

50 Having thus described my invention, what I claim as new and desire to secure by Letters Patent is:

1. The combination of a plurality of engine cylinders arranged in synchronously 55 charging and exhausting sets; a charging cylinder for each set of engine cylinders; pistons for said engine and charging cylinders; a common crank shaft to which said pistons are connected; a carbureter; inlet 60 chambers for said charging cylinders connected to said carbureter; a common discharge chamber for said charging cylinders; a valve-controlled by-pass connection for said charging cylinders; and delivery con- 65 nections from said charging chamber to said

engine cylinders comprising headers on said cylinders, and inlet valves for said cylinders opening into said headers.

2. The combination of a plurality of engine cylinders arranged in synchronously 70 charging and exhausting sets; a charging cylinder for each set of engine cylinders; pistons for said engine and charging cylinders; a common crank shaft to which said pistons are connected; a carbureter; inlet 75 chambers for said charging cylinders connected to said carbureter; a common discharge chamber for said charging cylinders; and delivery connections from said charging chamber to said engine cylinders comprising 80 headers on said cylinders, and inlet valves for said cylinders opening into said headers.

3. The combination of a plurality of engine cylinders arranged in synchronously 85 charging and exhausting sets; a charging cylinder for each set of engine cylinders; pistons for said engine and charging cylinders; a common crank shaft to which said pistons are connected; a common discharge chamber for said charging cylinders; a 90 valve-controlled by-pass connection for said charging cylinders; and delivery connections from said charging chamber to said engine cylinders comprising 95 headers on said cylinders, and inlet valves for said cylinders opening into said headers.

4. The combination of a plurality of engine cylinders arranged in synchronously 100 charging and exhausting sets; a charging cylinder for each set of engine cylinders; pistons for said engine and charging cylinders; a common crank shaft to which said pistons are connected; a common discharge chamber for said charging cylinders; and delivery connections from said charging 105 chamber to said engine cylinders comprising headers on said cylinders, and inlet valves for said cylinders opening into said headers.

5. The combination of a plurality of engine cylinders arranged in synchronously 110 charging and exhausting sets; a charging cylinder for each set of engine cylinders; delivery connections from said charging cylinders to said engine cylinders; pistons for said engine and charging cylinders; and a common crank shaft to which said pistons are connected, all coacting for the purpose 115 specified.

6. The combination of a plurality of engine cylinders arranged in synchronously 120 charging and exhausting sets; a charging cylinder for each set of engine cylinders; a common charging chamber to which said charging cylinders deliver; a valve controlled by-pass connection for said charging cylinders; and delivery connections from said charging chamber to the engine cylinders, all coacting for the purpose specified.

7. The combination of a plurality of engine cylinders arranged in synchronously 125

charging and exhausting sets; a charging cylinder for each set of engine cylinders; a common charging chamber to which said charging cylinders deliver; and delivery connections from said charging chamber to said engine cylinders for synchronously charging all of the cylinders of a set.

8. The combination of a plurality of engine cylinders arranged in synchronously charging and exhausting sets; a charging cylinder for each set of engine cylinders; a common charging chamber to which said charging cylinders deliver; and delivery connections from said charging chamber to said engine cylinders for synchronously charging all of the cylinders of a set.

9. The combination of a plurality of engine cylinders arranged in synchronously charging and exhausting sets; charging cylinders for the sets of engine cylinders; delivery connections from said charging cylinders to said engine cylinders; and means for synchronously charging all of the cylin-

ders of a set from the same charging cylinder, all coacting for the purpose specified. 25

10. The combination of a plurality of engine cylinders arranged in synchronously charging and exhausting sets, and means for synchronously charging all of the cylinders of a set comprising a charging chamber, a 30 header for each set common to all of the cylinders of the set, and connections from said headers to said compression chamber.

11. The combination of a plurality of engine cylinders arranged in synchronously 35 charging and exhausting sets, and means for synchronously charging all of the cylinders of a set comprising a compression chamber common to all of the cylinders of a set.

In witness whereof, I have hereunto set 40 my hand and seal in the presence of two witnesses.

JOHN M. SAILER. [L.S.]
